Attest;

Geo. G. Crocker,
Edw. Dummer.

Inventor:

Henry F. Shaw.

UNITED STATES PATENT OFFICE.

HENRY F. SHAW, OF BOSTON, MASSACHUSETTS, ASSIGNOR OF TWO-THIRDS
TO JOHN W. WHITE, OF DEDHAM, MASSACHUSETTS, AND JAMES C.
FARMER, OF PROVIDENCE, RHODE ISLAND.

TRACTION-INCREASER FOR LOCOMOTIVES.

SPECIFICATION forming part of Letters Patent No. 353,714, dated December 7, 1886.

Application filed April 12, 1886. Serial No. 193,623. (No model.)

To all whom it may concern:

Be it known that I, HENRY F. SHAW, a citizen of the United States, residing at Boston, in the county of Suffolk and State of Massachusetts, have invented a new and useful Device for Increasing the Traction of Locomotive-Wheels, of which the following is a specification, reference being had to the accompanying drawings.

10 The object of my invention is to increase the traction of the wheels of a locomotive in proportion to the draft required to move the train; and it consists in the device hereinafter set forth, whereby the driving-wheels are caused, by means of said draft, to support more of the weight of the locomotive than ordinarily supported by them.

15 In the drawings, Figure 1 is a side view of so much of a locomotive embodying my invention as is needful for illustration of the same. Fig. 2 is a plan. Fig. 3 is a section of one of the cylinders containing the springs, drawn on a larger scale.

The locomotive—of which parts are shown—20 is one in which there are four driving-wheels. Fig. 1 shows the two driving-wheels at the farther side, those at the nearside being removed. In the plan the four driving-wheels are shown. Two driving-wheels, A and B, are on the axle C, and two, D and E, are on the axle F. There is the ordinary frame, consisting of the longitudinal rails G and H and transverse pieces I and J. At the under side of the longitudinal rails are jaws a, which hold the boxes for 25 the axles—namely, the boxes K and L for the axle C, and the boxes M and N for the axle F. Each box may slide up and down between its jaws, as is common, the usual springs—which it is not deemed necessary to show in the drawings—intervening between the boxes and body 30 of the locomotive. The ordinary truck, having the four truck-wheels b, supports the forward end of the locomotive.

I pivot on the rail G at c a lever, O, and on 35 the rail H a lever, P, at d. For convenience' sake these levers are angular, the one O having the arms e and f, and the one P having the arms g and h. Each of the arms h and f straddles a rail—that is, is of two parts, one each

side of the rail, each of which parts bears at 50 its end on a box. To the upper end of the lever O is pivoted a cylinder, Q, and to the upper end of the lever P is pivoted a like cylinder, R. In each of these cylinders is a piston or plate, i, to which is connected one end of a rod 55 which extends through a hole in the end j of the cylinder. Between the piston or plate i and the end j is a spring, k. The rods S and T extend to the rear of the locomotive, where they are fastened to a cross-piece, U, which is 60 so supported that it may have a slight movement to and fro in a direction longitudinal with the locomotive. The rods S and T are shown as extending through the transverse piece J, wherein they may slide. At the middle 65 of the cross-piece U is fastened a draw-head, l, wherein may be held by a pin, m, the ordinary link, n, by which the tender and train of cars may be coupled with the locomotive.

Now, it will be understood from the above 70 description that the draft of the train will act directly to swing the levers O and P upon their pivots and cause the ends of their arms h and f to press upon the boxes thereunder, and hence the tendency will be to raise the forward part of the frame of the locomotive and 75 that part of the locomotive which is supported thereby, bringing the weight thereof upon the boxes K and L, and therefore upon the wheels A and B. Thus that part of the 80 weight of the locomotive which when there is no draft by the train is supported by the truck-wheels will be brought to bear upon the driving-wheels to a greater or less degree, according to the amount of said draft, and hence the 85 traction of the driving-wheels will be proportionally increased.

The cylinders Q and R and springs therein are merely to provide a simple device whereby there may be certain elasticity between the 90 place of coupling the train and the levers O and P, to prevent breaking the mechanism under a sudden strain. Such elasticity might be provided by other well-known devices, which might be interposed between the above-named 95 places of connection. So, too, there may be other modifications and a device be produced equivalent, substantially, to that described

above in detail, and one embodying my invention.

I claim as my invention—

1. A lever interposed between the frame or body of the locomotive and an axle for the driving-wheels, and connected with the tender or train, substantially as and for the purposes set forth.

2. A lever pivoted on the frame of a locomotive, bearing upon a box for an axle, and connected with a device for coupling with the tender or train, substantially as and for the purpose hereinbefore set forth.

3. In a locomotive, a lever pivoted to the locomotive and bearing at one end on a box for

an axle of the locomotive, in combination with a device embodying a spring for connecting the other end of said lever with the tender or train, substantially as and for the purposes set forth.

20

4. The combination of levers O and P, each pivoted on the frame of the locomotive, boxes K and L, cylinders Q and R, containing springs, rods S and T, and cross-piece U, substantially as and for the purposes specified.

HENRY F. SHAW.
